UNITED STATES PATENT OFFICE.

ALFRED GEORGE FOX, OF LONDON, ENGLAND, ASSIGNOR TO THE BABCOCK & WILCOX COMPANY, OF BAYONNE, NEW JERSEY, A CORPORATION OF NEW JERSEY.

CHAIN-GRAVE STOKER.

Application filed January 24, 1924, Serial No. 688,122, and in Great Britain January 27, 1923.

My invention relates to chain grate stokers and more particularly to means for supplying forced draft to such stokers.

My invention will best be understood by reference to the following description taken with the annexed drawings, in which—

Fig. 1 is a view in vertical longitudinal section of a furnace installation containing an illustrative embodiment of my invention, the section being taken on the line 1—1 of Fig. 2 except for the valve at the left of Fig. 1 which is a section taken on the line 1^a—1^a of Fig. 2;

Fig. 2 is a view in section taken on line 2—2 of Fig. 1;

Fig. 3 is a view chiefly in longitudinal section of a modified form taken on the line 3—3 of Fig. 4;

Fig. 4 is a view in section taken on line 4—4 of Fig. 3;

Fig. 5 is a side elevation of an arrangement similar to that shown in Fig. 3, with a large part of Fig. 5 in section on the line 5—5 of Fig. 6 and with part of the chain grate broken away to show a sprocket wheel;

Fig. 6 is a plan view of the arrangement shown in Fig. 5 with the chain grate removed.

Referring to Figs. 1 and 2, 10 denotes a chain grate which in the form therein shown is provided with a conduit 11 at one side of the grate for supplying forced draft thereto. The air from conduit 11 is fed beneath the grate into a plurality of transverse draft boxes 12 communicating with said conduit by means of ducts 13. For the purpose of collecting solid particles of ash and fuel which sift through the grate, the draft boxes 12 are provided with downwardly converging sides, as shown, terminating in arc-shaped guides or valve seats 14, providing upper openings 12^a and lower openings 12^b. In the valve seats thus formed are located substantially cylindrical, hollow drums or valves 15 having slots 16 extending along them. For substantially continuous operation of valves 15, I preferably provide at each end thereof sprocket wheels 17, the teeth of which mesh with links 18 of the underside of chain grate 10. It will thus be seen that the valve 15 will be given a continuous rotation during the operation of the grate and that whenever a slot 16 moves into register with slot 12^a of the valve seat 14 it will receive a charge of the solid par-

ticles, or "riddlings", which have sifted through the grate, and when said slot is moved into register with slot or opening 12^b the material will be discharged therethrough, without, however, the forced draft at any time having an opportunity to escape through the valve opening.

In Figs. 3 and 4 I have shown a somewhat modified form particularly adapted for use in grates of considerable width and which would necessitate unduly long valves 15, or where there would be insufficient space for the location of a conduit 11 at the side of the grate.

In the embodiment shown I provide a transverse air conduit 20 which communicates with a central longitudinal duct 21, preferably of triangular cross section, the sides of the triangle diverging downwardly, as shown. Communicating with longitudinal duct 21 are a plurality of cross ducts 22, which in turn communicate with transverse draft boxes 23 having downwardly converging sides 23^a, as in the previous embodiment. The sides 23 terminate in the valve seats 14' provided with valves 15' similar to valves 14 and 15, above described, and which are operated by sprocket wheels 17', the teeth of which mesh with links 18' of the underrun of chain grate 10'. The operation of valves 15' is in all respects the same as that of valves 15, above described.

The draft box 23 at the left of Fig. 3 communicates with the transverse conduit 20 and the remaining draft boxes 23 communicate with cross ducts 22, the openings preferably having valves or dampers 24, the position of which may be adjusted as shown, to control the amount of forced draft delivered to different portions of the grate. By this arrangement the length of the valves is kept within practicable limits, the air is more evenly distributed, and in addition, the solid particles sifting through the grate are prevented from falling into and choking up the main air conduit 21. It will also be noted that by making the conduit 21 of substantially triangular cross section with the sides diverging downwardly, the minimum amount of area of the chain grate is sealed off against the ingress of air, while the conduit can be made of substantial capacity.

In Figs. 5 and 6 I have illustrated a slightly modified form in which the essential features of the last described modification are

preserved, but which is particularly adapted to grates in which the width is not excessive. In this construction a transverse draft conduit 20^a communicates with a central, longitudinal duct 21^a, preferably of triangular cross section, as in the preceding construction. Duct 21^a terminates in a chamber 25 which also serves as a draft box and which extends across the surface of the grate. 5 Chamber 25 communicates with forward draft boxes 26, 26 located on either side of duct 21^a by means of ports having controlled valves or dampers 27 and communicates with a rear draft box 28 extending across the grate surface by means of a port having a controlled damper 29. Chamber 25 is provided with a plurality of downwardly recessed portions 30 in which the solid particles sifting through the grate collect, each of which is provided with a valve 15^a and attendant operating mechanism, the same as described for the previous embodiments. The walls of draft box 28 converge toward the valve 15^a at the bottom of the box. 10 25 In forced draft furnaces employing chain grates as commonly used, difficulties arise in supplying forced draft particularly in the case of wide and inside grates; in the case of wide grates when the air under pressure is brought in at the sides as is usual, it is difficult to cause it to be supplied evenly over the entire surface of the grate. This is particularly so in the case of middle portions of the grate where a proper supply of draft 30 is more necessary than it is at the side. In the case of inside grates, moreover, the sides are often too restricted to allow outside ducts. Furthermore, a substantial obstacle to the efficient design of draft box has been 35 that small particles of solid matter consisting of burned or unburned fuel or "riddlings" pass through the apertures in the grate and choke up the draft passages unless special means be taken to remove them as fast as they collect. 40 45 It will be seen that I have provided simple and efficient means for overcoming the above-mentioned difficulties, and that I have provided means operated by the movement of the grate itself for continuously removing the solid particles as fast as they collect. Moreover, I have provided a special arrangement of air ducts which provide an efficient distribution of forced draft whether located 50 within or without the stoker. In the former case it will be seen that I have in addition provided means whereby the distribution of the draft may be accurately controlled and the amount supplied to different parts of the grate diminished or increased as may be required. 55 60 65

I claim:

1. In a chain grate stoker, a plurality of draft boxes between the upper and lower runs of the grate, a conduit supplying draft

to said boxes, said boxes receiving solid particles sifting through the grate and shaped so as to collect such particles in a lower portion of each box, valves in said portions permitting discharge of said particles while maintaining a seal against the escape of air from the boxes, and means cooperating with said grate for operating said valves. 70

2. In a chain grate stoker, a plurality of draft boxes between the upper and lower runs of the grate, a conduit supplying draft to said boxes, said boxes receiving solid particles sifting through the grate and shaped so as to collect such particles in a lower portion of each box, rotary valves in said portions permitting discharge of said particles while maintaining a seal against the escape of air from the boxes, and means cooperating with said grate for operating said valves comprising a sprocket wheel for each valve 80 meshing with the links of the chain grate. 85

3. In a chain grate stoker, a plurality of transverse draft boxes between the upper and lower runs of the grate, each of said boxes being open at the top to receive solid particles sifting through the upper run of the grate and having its sides converging downward to collect such particles in the lower narrow part of the box, and each box having a valve in its bottom arranged to permit discharge of such particles onto the lower run of the grate while maintaining a seal against the escape of air from the box, and a conduit supplying draft to said boxes. 90 95 100

4. In a chain grate stoker, a longitudinal, substantially central draft conduit beneath the upper run of the grate, transverse draft boxes on each side of said conduit and communicating therewith, each of said boxes being open at the top to receive solid particles sifting through the upper run of the grate and having its sides converging downward to collect such particles in the lower narrow part of the box, and each box having a valve in its bottom arranged to permit discharge of such particles onto the lower run of the grate while maintaining a seal against the escape of air from the box, and a conduit supplying draft to said boxes. 110 115

5. In a chain grate stoker, a longitudinal, substantially central draft conduit beneath the upper run of the grate, transverse draft boxes on each side of said conduit and communicating therewith, each of said boxes being open at the top to receive solid particles sifting through the upper run of the grate and having its sides converging downward to collect such particles in the lower narrower part of the box, each box having an opening in one of its converging sides for the admission of the draft, and each box having a valve in its bottom arranged to permit discharge of such particles onto the lower run of the grate while maintaining a seal 120 125 130

against the escape of air from the box, and a conduit supplying draft to said boxes.

6. In a chain grate stoker, a longitudinal, substantially central draft conduit beneath the upper run of the grate, transverse draft boxes on each side of said conduit, each of said boxes being open at the top and having its sides converging downward, the sides of adjacent draft boxes being spaced apart to 10 form cross ducts between said boxes, the inner ends of said cross ducts communicating with said central conduit, and each draft box having an air inlet port in one of its converging walls and communicating 15 with one of said cross ducts.

7. In a chain grate stoker, a longitudinal, substantially central draft conduit beneath the upper run of the grate, transverse draft boxes on each side of said conduit, each of 20 said boxes being open at the top and having its sides converging downward, the sides of adjacent draft boxes being spaced apart to 25 form cross ducts between said boxes, the inner ends of said cross ducts communicating 30 with said central conduit, and each draft box having an air inlet port in one of its converging walls and communicating with one of said cross ducts, and a valve in the bottom of each of said draft boxes arranged to permit discharge of such particles onto the lower run of the grate while maintaining a seal against the escape of air from the box.

8. In a chain grate stoker, a longitudinal,

substantially central draft conduit beneath 35 the upper run of the grate, transverse draft boxes on each side of said conduit, each of said boxes being open at the top and having its sides converging downward, the sides of adjacent draft boxes being spaced apart to 40 form cross ducts between said boxes, the inner ends of said cross ducts communicating with said central conduit, and each draft box having an air inlet port in one of its 45 converging walls and communicating with one of said cross ducts, and dampers for controlling said inlet ports.

9. In a chain grate stoker, a longitudinal, substantially central draft conduit beneath 50 the upper run of the grate, transverse draft boxes on each side of said conduit, each of said boxes being open at the top and having its sides converging downward, the sides of adjacent draft boxes being spaced apart 55 to form cross ducts between said boxes, the inner ends of said cross ducts communicating with said central conduit, and each draft box having an air inlet port in one of its converging walls and communicating 60 with one of said cross ducts, a valve in the bottom of each of said draft boxes arranged to permit discharge of such particles onto the lower run of the grate while maintaining a seal against the escape of air 65 from the box, and means cooperating with said grate for operating said valves.

ALFRED GEORGE FOX.
